BUILDER'S HOIST

Oakley Schuchert, Iowa City, Iowa

Application July 12, 1947, Serial No. 760,560

10 Claims. (Cl. 187—2)

1

This invention relates generally to hoists and in particular to a builder's hoist for lifting materials used in the erection of a building.

An object of this invention is to provide an improved builder's hoist.

A further object of this invention is to provide a builder's hoist of a knock-down construction capable of being easily handled by one man for transport from job to job and readily adapted for use on structures of widely varying heights.

Another object of this invention is to provide a builder's hoist, including a mast comprised of separably connected sections and a lift movable on the mast, in which an additional section for lengthening the mast can be carried to the top of the mast on the lift, after which the lift is locked against downward movement to constitute a working platform while the additional section is being assembled on the mast.

Still a further object of this invention is to provide a builder's hoist having a mast comprised of separably connected interchangeable sections of a construction such that a pulley support is connectible to the upper end of the mast for any height of the mast.

A further object of this invention is to provide a builder's hoist having a mast which is supported in an upright spaced relation from a structure being erected by connecting frames connectible between the mast and such structure at a plurality of positions longitudinally of the mast.

Another object of this invention is to provide a builder's hoist in which a lift carries a rotatable wheelbarrow supporting frame to facilitate handling of the wheelbarrow from a scaffold.

Still a further object of this invention is to provide a builder's hoist which is of a simple and rugged construction, capable of being easily and quickly assembled for application to structures varying widely in height, adapted to be knocked down into individual package units for convenient handling by one man, efficient in operation, and capable of lifting a wide variety of building materials.

A feature of this invention is found in the provision of a builder's hoist having a mast comprised of sections of a like construction capable of being connected end to end. A support, for a cable-carrying pulley, is attachable on the upper end of the top mast section. Means are provided to hold a lift in an elevated position, independently of a hoist mechanism therefor. An additional section for the mast, therefore, can be lifted to the top of the mast, and on locking of the lift against downward movement, the pulley

support is removable from the top of the mast and attachable to one end of the additional section, after which such section is connected at its opposite end on the mast. In this operation the lift functions as a stationary working platform. An extension of the mast, as required in the erection of a structure, is thus readily accomplished by utilizing the hoist itself for such purpose.

Yet another feature of this invention is found in the provision of a builder's hoist, in which a sectional mast of a metal construction is formed along one side with a series of longitudinally spaced tapped holes. To hold the mast in an upright position adjacent to the wall of a structure being erected, there is provided a plurality of like frame structures each of which includes a base member capable of being secured on the wall in a horizontally extended position. A connecting member is pivotally connected at one end to opposite ends of the base member, and carries a bolt at its other end which is threadably connectible with one of the tapped holes in the mast.

Further objects, features and advantages of this invention will become apparent from the following description when taken in connection with the accompanying drawings, in which:

Fig. 1 is a front elevational view of the builder's hoist of this invention shown in a supported relation with the wall of a structure being erected;

Fig. 2 is a side elevational view of the hoist, looking toward the right in Fig. 1, with the structural wall removed for the purpose of clarity.

Fig. 3 is a fragmentary exploded perspective view of a pair of adjacent connected ends of the sections comprising the mast;

Fig. 4 is an enlarged sectional detail view taken on the line 4—4 in Fig. 2;

Fig. 5 is a fragmentary detail perspective view showing the connection of the mast with a base section therefor;

Fig. 6 is an enlarged sectional view taken on the line 6—6 in Fig. 2, with certain parts removed for clarity;

Fig. 7 is a sectional view as seen on the line 7—7 in Fig. 6;

Fig. 8 is an enlarged sectional view as taken on the line 8—8 in Fig. 2 showing a connecting frame for supporting the masts from a wall structure being erected;

Fig. 9 is an enlarged sectional detail view on the line 9—9 in Fig. 2, showing the relative assembly of the hoist mechanism with the mast; and

Fig. 10 is a sectional view taken on the line 10—10 in Fig. 9.

With reference to the drawings, the hoist of this invention is illustrated in Figs. 1 and 2 as having a mast 15, a lift 16 movably supported for up and down movement on the mast, and a hoist mechanism 17 for operating the lift, and including a cable 18.

The mast 15 is comprised of a plurality of separably connected sections 19 (Figs. 2 and 3) each of which is of a substantially I-shape in transverse cross section. Each end of a mast section 19 carries oppositely arranged pairs of tube or pipe lengths 21 which are secured, as by welding, to the outer surfaces of the section side members 22 and 22a at positions within the transverse and longitudinal confines of a mast section 19, such that corresponding tubes 21, at opposite ends of a section 19, are in alignment longitudinally of the section.

In the assembly of the mast 15 the sections are arranged in an end to end relation, so that the tubes 21 are in coaxial alignment. Bolts 23 are then inserted through each pair of adjacent coaxially aligned tubes 21. On tightening of the nuts 24, for the bolts 23, the sections 19 are firmly secured together in longitudinal alignment.

Also, as shown in Figs. 2 and 3, the mast sections 19 are provided along their sides 22a with a series of longitudinally spaced tapped holes 26 which terminate in transverse openings 27 formed in the connecting web 28 between the section side members 22 and 22a. The openings 27 provide for the holes 26 being tapped for a distance corresponding substantially to the thickness of the side members 22a, for a purpose which will appear later. It is contemplated that each mast section 19 be about six feet long with the end openings 27a, as indicated in Fig. 2, being spaced about six inches from the corresponding ends of the section 19, and with the remaining intermediate openings 27 being spaced about twelve inches apart. As a result, in the assembled mast 15, each opening 27 and tapped hole 26 is spaced twelve inches apart from a next adjacent opening and tapped hole.

A pulley attachment 30 carried at the upper end of the mast 15, for movably supporting the lift cable 18, includes a pulley 29 rotatably carried in a bracket 31 having a base member 32 (Figs. 1, 2 and 4).

The base 32 is formed with openings 33 arranged in a spaced relation corresponding to the spaced relation of the tubes 21 at opposite ends of the mast sections 19. In the assembly of the pulley attachment 30 with the upper end of the mast 15, bolts 23 are extended through the openings 33 and through the tubes 21 at the upper end of the mast. On tightening of the bolt nuts 24, the pulley attachment is positively secured to the mast. It will be understood, of course, that this assembly of the pulley attachment at the upper end of the mast 15 will be the same for any height of the mast as determined by the number of mast sections in the mast.

The bottom of the lowermost mast section 19 is secured to a mast base member 34 by inserting bolts 23 through the tubes 21 at the bottom of such lowermost section for threadable connection with tapped openings (not shown) formed in the base member 34 in a spaced relation corresponding to the spaced relation of the tubes 21.

The mast 15 is supported in an upright position spaced from the wall 36 (Fig. 1) of a struc-

ture being erected by the provision of means including a plurality of connecting frames 37 (Figs. 1, 2 and 8). The frames 37 are illustrated as applicable to a brick wall construction, and each frame includes a stationary support or base member 38 of an angle iron construction provided at opposite ends with bearing members 39. The base 38 is secured in a substantially horizontal position on the wall structure 36 by a bolt 41 extendible through a vertical leg 42 thereof and into the mortar 43 between adjacent bricks in the wall 36.

A substantially V-shape pivoted member 44 has the free ends of its legs pivoted at 46 in the bearing members 39 of the base 38 to provide for an up and down pivotal movement of the member 44. A bolt 47 extends through the apex 48 of the pivoted frame 44 for threadable connection with a mast section 19 at a tapped hole 26 therein. A collar or spacer member 45 is mounted on the bolt 47 between the member 44 and the side member 22a of a mast section.

By virtue of the spacing of the tapped holes 26 longitudinally of the sections 19, it is apparent that the mast is capable of being supported at any desired number of positions with the wall 36. The pivoted member 44 readily accommodates any variation in the vertical disposition of the bolt 47 relative to a tapped opening 26, an its V-shape construction and double connection with the base 38 acts to hold the mast 15 against a tipping movement in any direction.

The lift 16 (Figs. 1, 2, 6 and 7) includes a pair of side frame members 49 of a channel iron construction and of a substantially L-shape. The frame members 49 are arranged at opposite sides of the mast 15 such that their long legs 51 extend horizontally outwardly from the side members 22 of the mast sections 19, and their short legs 52 vertically upwardly at positions substantially opposite the longitudinal edges of the side members 22. A platform 53 is connected, as by welding, across the top sides of the long legs 51, and a brace plate 54 is connected, also by welding, across the top outer sides of the short legs 52 so as to be spaced outwardly from the mast side members 22 in a plane substantially parallel therewith.

Upright plate members 56, secured to the inner adjacent sides of the short legs 52, and of a length substantially coextensive with such legs, carry vertically spaced stub shafts 57 for rotatably supporting flange rollers 58 at positions arranged to opposite sides of the connecting web 28 of a mast section 19, for contact engagement with the inner surface of the mast side members 22 and 22a. The rollers 58 and side members 22 and 22a thus coact to guidably support the lift 16 for up and down movement on the mast 15.

The cable 18 is movably supported on the pulley 29, intermediate its ends, so that one of its lengths is arranged adjacent to the side members 22a of the sections 19, and the other of its lengths adjacent to the side members 22. The end 59 (Fig. 1) of the cable 18 is of a yoke construction to provide for its connection at 61 with opposite end portions of the plate member 54 connected between the short legs 52 of the frame members 49.

The opposite end 62 of the cable 18 (Figs. 9 and 10) is connected to a winding drum 63 forming part of the hoist mechanism 17. The drum 63 is mounted on the projected end 64 of a shaft

66 which forms part of a speed reduction unit, designated generally as 67, secured as by bolts 68 to one leg 69 of an angle plate member 71. The other legs 72, of the angle member 71, is connected to the side member 22a of the lowermost mast section 19 by bolts 73 extended therethrough and threadably engageable with the mast section at certain of the tapped holes 26 therein.

A drive shaft 74 for the speed reduction unit 10 67 is connected through a belt 76 with a drive pulley 77 of an electric motor 78 (Figs. 1 and 2). The motor 78 is carried on a frame 79 which is pivotally supported for up and down movement at 15 65 on the legs 69 of the angle member 71. Pivoted adjustable movement of the frame 79, for the purpose of adjusting the tension in the belt 76, is accomplished by the provision of a bolt 75 20 15 threadably connected at its lower end 85 in a plate member 86 secured to the top of the speed reduction unit 67, and having its upper end pivoted at 10 with the frame 79. Thus by merely adjusting the bolt 75, the frame 79 is pivotally adjusted in an up and down direction to vary the tension in the belt 76.

The winding drum 63 is formed of two coaxially aligned sections 81 and 82, with the section 81 constituting what shall be hereinafter referred to as a reserve section, and the section 82 as an active section (Figs. 9 and 10). The sections 81 and 82 are separated by a flange member 83 having a notch 84 cut therein for receiving the cable 18. The amount of live cable to be wrapped about the active section 82 of the winding drum 63 is determined by the working height of the mast 15. In other words, when the mast 15 is relatively short, only a small length of live cable will be wound about the active drum section 82, and a greater length of cable 18 will be wrapped about the reserve drum section 81, with the portion of the cable 18, indicated as 18a, and extended through the notch or cut 84, defining the termination of the live cable length. By virtue of this construction of the winding drum 63, a relatively long cable 18 can be used on a plurality of jobs requiring different mast heights, without necessitating any cutting of the cable 18.

It is contemplated that the motor 78 be of a reversible type, and the speed reduction unit 67 of a worm gear type, as illustrated in Fig. 9, so that the operation of the motor will control the rate of travel of the loading platform 16 in its up and down movements. For this purpose a reversing switch, indicated generally as 86 (Fig. 2) is carried on an extended portion 87 of the plate member 86.

From the above description it is seen that the hoist mechanism 17 is detachably connected with the mast 15 through the bolts 73. Further, the mast sections 19 are separably connected by means of the tubes 21 and bolts 23 and the lowermost section 19 in the mast 15 is detachably connected with the mast base 34 by bolts 23. The connecting frames 37 are detachably connected with the wall structure 36 and the mast 15 through the bolts 41 and 47, respectively, while the lift 16 is separable from the mast by merely moving the rollers 58 out of their assembly relation with the mast sections. As a result the hoist is capable of being knocked down into a relatively few number of compact package units which can be easily handled by one man for transport and assembly purposes. The complete hoist, when dis-assembled, can be thus readily carried from job to job in a pickup truck.

In the use of the hoist the lift 16 is assembled with the lowermost section 19, after which such section 19 is assembled with the mast base 34. The hoist mechanism 17 is then connected with the lowermost mast section by the bolts 13. The pulley attachment 39, if desired, can be assembled at the upper end of the lowermost mast section for low lift work.

In the assembly of an additional section 19 on the mast, to increase its height, such additional mast is loaded on the platform 34 and the hoist 17 operated to elevate the lift to its highest position on the mast. With the lift thus elevated, a locking pin 89 (Fig. 3) is inserted through the opening 27, immediately below the lowermost rollers 58. The lift 16 is then lowered by operation of the hoist mechanism until the bottom rollers 58 are supported on the locking pin 89. The lift 16 is thus positively locked against downward movement, independently of the hoist mechanism 17.

With the lift thus locked, the platform 34 constitutes a working platform for the hoist operator, whereby the upper end of the mast is easily accessible. The pulley attachment 38 is then removed from the upper end of the mast, and the additional mast section, which was previously elevated by the lift 16, is assembled and placed on the mast so as to constitute the uppermost section in the mast. Prior to this assembly of the additional mast section, with the erected mast 15, the pulley attachment is assembled on one of its ends. With the additional mast in its assembly position the hoist mechanism 17 is again completely operative to raise and lower the lift 16. The hoist mechanism is initially operated to elevate the lift so as to move the lower rollers 58 out of engagement with the locking pin 89.

It is to be understood that this assembly of an additional mast section, with the erected mast 15, is the same for any height of the erected mast. Likewise, successive connecting frames 37 are connected between the mast 15 and a wall structure 36, as the mast is progressively lengthened.

To facilitate the handling of bulk material, such as cement and mortar, which are usually carried in a wheelbarrow, the platform 34 is formed with an open bearing 92 (Fig. 7) at a position intermediate and adjacent to the outer ends of the long legs 51 of the channel side members 49. The bearing 92 is adapted to rotatably receive a stub shaft 93 projected downwardly from the lower side of a wheelbarrow support 94. A fiber member or the like 96, mounted about the shaft 93, is interposed between the underside of the wheelbarrow support 94 and the top side of the platform 34 to retard a free rotational movement of the wheelbarrow support.

As best appears in Fig. 6, the wheelbarrow support 94 is of a substantially triangular shape, with an intermediate section 97 of the base thereof being bent downwardly to form a ramp for the wheelbarrow. The sections 98, at opposite sides of the ramp 97, are upturned at 99 and the apex of the wheelbarrow support 94 is upturned at 101 to form stops. Thus on running a wheelbarrow up the ramp 97 on to the support 94, its wheel is positioned against the stop 101, while its supporting legs are carried on the base end sections 98 adjacent to the stops 99 so as to prevent movement of the wheelbarrow off of the support 94 during the operation of the lift 16.

75 When the wheelbarrow support 94 is not in use,

the shaft 93 is merely lifted out of the bearing 92, with the open construction of the bearing preventing any accumulation of material, dirt or the like therein, which interfere with a later assembly of the wheelbarrow support 94 on the platform 53.

From a consideration of the above description it is seen that this invention provides a builder's hoist which is of a compact and rugged construction, readily applicable for use in the construction of buildings of widely varying heights, and capable of efficiently handling bulk and solid building materials. Further, the hoist is of a construction to provide for its being knocked down into a relatively few number of units of a size and weight readily handled by one man for transport and assembly purposes. Also, the lift is fully utilized in the assembly of additional mast sections on an already erected mast. As a result substantially no inconvenience or loss of time is encountered in progressively increasing the height of the mast to accommodate the increase in height of a building being erected.

Although the invention has been described with respect to a preferred embodiment thereof, it is to be understood that it is not to be so limited since changes and modifications can be made therein which are within the full intended scope of this invention, as defined by the appended claims.

I claim:

1. A builder's hoist including a mast comprised of a plurality of separably connected one piece sections, means for connecting together adjacent ends of said sections, a lift movably supported on said mast for up and down movement, a hoist mechanism carried on said mast, a cable supporting unit adapted for detachable connection with either end of a section and carried on the upper end of the top section of said mast, a cable adapted to travel over said unit and operatively associated with said hoist mechanism and lift, means independent of said hoist mechanism for holding said lift in an elevated position against downward movement to provide for an additional mast section being carried upwardly on said lift for assembly with the upper mast section to extend said mast, and means connectible with said sections and a structure being built to support said mast in an upright position.

2. A builder's hoist including a mast comprised of a plurality of separably connected one piece sections of a generally I-shape in transverse cross section, means for connecting said sections together including longitudinally extended tubes arranged about the opposite ends of each section and within the planes of the end faces at said opposite ends, clamp means extendible through adjacent tubes, a cable carrying pulley, and means for rotatably supporting said pulley on the upper end of the topmost section in the mast, including a base member having openings therein arranged in a spaced relation corresponding to the arrangement of the tubes at the end of a mast section.

3. A builder's hoist including a mast comprised of separably connected one piece sections of a generally I-shape in transverse cross section, a lift, means movably supporting said lift for up and down movement on said mast including rollers guidably arranged between the side portions of said sections at opposite sides of the connecting web therebetween, hoist means for raising and lowering said lift, with one of said side portions having a series of longitudinally spaced tapped

holes therein terminating in transverse openings in said web, means insertible through a transverse opening and engageable with a roller to hold said lift against downward movement independently of said hoist means, and means connectible with a section at a tapped opening therein and with the structure being erected to support said mast in an upright position.

4. A builder's hoist including a mast comprised of separable sections, a lift movably supported on said mast for up and down movement, a hoist mechanism mounted on said mast adjacent the lower end thereof, flexible lifting means having one end connected with said mechanism and an opposite end connected with said lift, means at the top of said mast for movably supporting said lifting means intermediate the ends thereof, and means detachably supported on said mast in the path of movement of said lift for holding said lift in a selected elevated position independently of said hoist mechanism, whereby to relieve said lifting means of any load.

5. In a builder's hoist, a mast comprised of a plurality of separably connected one piece sections of a substantially I-shape in transverse cross section, longitudinally extended tubular members carried at the ends of said sections in a predetermined spaced relation, with the outer ends of said tubular members being within the longitudinal confines of said sections, a rotary member for movably supporting a flexible lifting means at the top of the uppermost section, a bracket support for said rotary member including a base member having openings arranged therein in a spaced relation corresponding to the spaced relation of said tubular members, and clamp means extendible through longitudinally aligned tubular members at the adjacent ends of said sections, and through the openings in said base member and the tubular members at the top of said uppermost section.

6. In a builder's hoist including a mast, means for supporting said mast in an upright position spaced from a structure being erected including a frame structure comprised of a horizontal member, means for attaching said horizontal member to the structure being erected, a member of a substantially V-shape, a first means pivotally connecting the free ends of the legs of said V-member with opposite ends of said horizontal member, and second means pivotally connecting the apex of said V-member with said mast, with the axes of said first and second means being in a parallel relation.

7. In a builder's hoist including a mast, means for supporting said mast in an upright position spaced from a structure being erected including a first member, means for attaching said first member in a horizontally extended position on said structure, a second member having a pair of spaced portions at one end thereof pivotally connected to opposite ends of said first member, and means for pivotally connecting the other end of said second member to said mast, with the axes of the pivotal connections at opposite ends of said second member being in horizontal planes.

8. A builder's hoist including a mast comprised of a plurality of separably connected one piece sections of a generally I-shape in transverse cross section, means for connecting said sections together in longitudinal alignment including fixed camping members arranged about the opposite ends of each section and within the planes of the end faces at said opposite ends,

and movable clamping members in detachable engagement with adjacent fixed clamping members, a cable carrying pulley, and means for rotatably supporting said pulley on the upper end of the topmost section of said mast including a base member having fixed clamping portions arranged in a spaced relation corresponding to the arrangement of the fixed clamping members at the end of a mast section.

9. A builder's hoist including a mast comprised of separably connected one piece sections of a generally I-shape in transverse cross section, a lift, means movably supporting said lift for up and down movement on said mast including rollers guidably arranged between the side portions of said sections at opposite sides of the connecting web therebetween, hoist means for raising and lowering said lift, said connecting web having a series of longitudinally spaced transverse openings therein, means insertible through a transverse opening and engageable with a roller to hold said lift against downward movement independently of said hoist means, and means connectible with a section and with the structure being erected to support said mast in an upright position.

10. A builder's hoist including a mast comprised of separable sections, a lift movably supported on said mast for up and down movement, a hoist mechanism mounted on said mast, flexible lifting means having one end connected with said mechanism and an opposite end connected with said lift, means at the top of said mast for movably supporting said lifting means intermediate the ends thereof, and means detachably supported on said mast in the path of movement of said lift for holding said lift in a selected elevated position independently of said hoist mechanism, whereby to relieve said lifting means of any load.
